KIRK S. HOOKS AND FLOYD L. HOOKS, OF PADUCAH, KENTUCKY.

RERAILING FROG.

Application filed May 7, 1926. Serial No. 107,500.

Our present invention has reference to a re-railing frog for directing derailed cars onto the rails of a track, and our primary object is the provision of a device for this

5 purpose which is of a comparatively simple construction, but strong and effective for successfully accomplishing its purpose.

A further object is the provision of a re-railing frog that is constructed of sections 10 secured together in a manner to produce a strong and rigid structure and whereby should any of the sections become worn or broken the same may be readily replaced by a similar section.

15 A still further object is the provision of a rerailing frog that comprises essentially a channeled member whose sides provide inclined planes, the elevated ends of which being straight and rounded outwardly away from each other, said channeled member having at its ends a toe and a heel member between which there is journaled a centrally arranged roller that is elevated above the inclined planes and that has one of its ends 20 flared outwardly to enlarge the same, the said flared portion being arranged opposite the outwardly rounded ends of the inclined planes, and whereby the tread portion of car wheels traveling over the inclined planes 25 will be effectively sustained thereon by the roller with a minimum amount of friction exerted against said wheel and also whereby a derailed train may be easily drawn by an engine onto the rails of a track.

30 A still further object is the provision of a rerailing frog, comprising a channeled member made up of removably connected sections and whose base is formed with an outwardly extending portion against which 35 the heads of spikes driven into ties contact, the sides of the channeled member providing inclined planes, whose elevated ends are straight but are rounded outwardly with respect to each other and terminate in projecting shoulders, one of which is designed 40 to rest on one of the rails of the track, said channel member having removably associated therewith toe and heel members that provide bearings for trunnions on the ends 45 of a roller, which latter is elevated above the inclined planes and has a flared end disposed opposite the outwardly rounded ends of the said planes and further wherein the heel member has swivelly associated therewith a hook designed to engage a rail for

holding the frog in proper position with respect thereto.

To the attainment of the foregoing and other objects which will present themselves as the nature of the invention is better understood, the improvement further resides in certain novel features of construction, combination and operative association of parts, a satisfactory embodiment of which is illustrated by the drawings which accompany and form part of this application.

In the drawings:

Figure 1 is a plan view of our improvement.

Figure 2 is a side elevation thereof.

Figure 3 is a sectional view approximately on the line 3—3 of Figure 2.

Figure 4 is a sectional view approximately on the line 4—4 of Figure 2.

Figure 5 is a sectional view approximately on the line 5—5 of Figure 1.

Figure 6 is a view of the hook.

As disclosed by the drawings we employ what we will term a channel member. The member comprises two sections. The base 80 portions of these sections are indicated by the numerals 1 and 2, respectively. The confronting end of the base member 1 is grooved longitudinally and that of the member 2 is formed with a tongue 3 to be 85 received in the groove. The sides of the members are indicated each by the numeral 4 and the base members outward of the sides 4 are formed with beveled flanges 5. The sides are in the nature of inclined planes, 90 that is the upper edge of each side is inclined downwardly from a point adjacent one end to its second end. The upper edges of the inclined planes are preferably flanged outwardly to provide the same with heads 95 6, and the elevated ends of the flanges, including, of course the heads 6 thereof, are straight or flattened, as at 7. These straight ends of the members are rounded outwardly, as clearly disclosed by Figure 1 of the drawings, and for distinction these rounded portions are indicated by the numerals 8.

For a determined distance from its lower end the base of the channel member is grooved longitudinally, as indicated by the numeral 9 and in this groove there is seated a tongue 10 formed on the base portion 11 of a toe member 12. The toe member is centrally formed with an upstanding longitudinally extending flange 13, the upper 110

face of which being grooved, as at 14. On its outer end the toe is formed with an upwardly projecting portion in the nature of a lug 15 and this lug, from its inner face, is provided with a round depression 16, the purpose of which will presently be described. Passing through the flanges 4 and through the base or body portion 11 of the toe there are bolts 17 which are engaged by nuts 18. In this manner it will be noted that the toe as well as the sections of the channeled member are removably associated.

Received between and contacting with the rounded ends 8 of the sides or inclined planes 4 there are the rounded edges of the base or body 19 of the heel member 20 of the improvement. There is passed through the base or body 19 and through the sides or inclined plates 4 of the channeled member one or more bolts 21 which are engaged by nuts 22. In this manner it will be seen that the heel is removably associated with the channel member. The base or body 19 of the heel is centrally formed with an upwardly extending lug that provides the heel proper, and the inner face of this lug is formed with a centrally arranged longitudinally extending rounded depression 23. The heel 20, on the outer edge thereof, is either formed with or has rigidly secured thereon a staple 24, and loosely connected with this staple there is one end of a flat plate 25. The outer end of this plate is upset to form the same with a hook 26, and this hook is designed to engage with one of the track rails 27 against which the frog is positioned. Each of the heads 6, at the heel portion of the device, is projected a suitable distance beyond the sides 4 thereof, and the under faces of these projecting portions provide shoulders 28 which rest on the head of the rail 27.

The rounded depressions or openings 16 and 23 receive therein trunnions 29 and 30, respectively, on the ends of a roller 31. The roller is elevated above the inclined planes and the end thereof provided with the trunnion 29 is enlarged, and from the said enlarged end the outer periphery of the said roller is flared inwardly, as at 31'. This flared portion of the roller conforms to the shape of the rounded ends 8 of the inclined planes, so that the space or passage between the inner faces of the planes and the outer surfaces of the roller are approximately equal throughout. The roller also finds a bearing in the depressed upper edge 14 of the flange or web 13.

Of course, two of the frogs are employed and are arranged to receive the tread of the wheels of a derailed car on the heads of the inclined planes, the flanges of the wheels traveling in the gap between the inclined planes and the elevated roller. The frogs may be spiked to the supporting ties and the

rails 27 and as previously stated the ledges 28 overlie the heads of the said rails 27 and the rails are engaged by the hooks 26. By hitching the derailed car to an engine and by properly positioning the frogs, the said derailed car may be easily and quickly drawn onto the track rails 27, regardless of the position of the derailed car with respect to the rails of the track. Of course, if desired, the derailed car may be manually shoved onto the track rails, and the simplicity of our construction and the advantages thereof, will, it is thought, be perfectly apparent when the foregoing description has been carefully read in connection with the accompanying drawings.

Having described the invention, we claim:

1. A rerailing frog including a channeled member whose sides comprise inclined planes, the elevated ends of which are rounded outwardly, a roller journaled centrally between said sides, elevated above the sides and having one of its ends flared and enlarged at a point opposite the outwardly rounded sides of the channel member.

2. A rerailing frog including a channeled member whose sides comprise inclined planes, the elevated ends of which are rounded outwardly, a roller journaled centrally between said sides, elevated above the sides and having one of its ends flared and enlarged at a point opposite the outwardly rounded sides of the channel member and a hook swivelly secured on the widened end of the member.

3. A rerailing frog, including a channeled member whose sides comprise inclined planes, whose elevated ends are straight and are rounded outwardly, each of said sides having their upper edges headed and the said heads project beyond the elevated ends of said sides, a roller journaled centrally between the sides, elevated thereabove and having one end flared outwardly and the said flared portion of the roller being disposed opposite the rounded ends of the sides and a hook on the elevated end of the frog.

4. A rerailing frog comprising a channeled member made up of two sections, the sides of the said member providing inclined planes whose upper edges are headed and whose elevated ends are straight and project beyond the elevated ends of the sides proper, a toe member between the sides and bolted thereto, a heel member having a web portion between the sides and bolted thereto, a roller having trunnion ends journaled respectively in the toe and in the heel and sustained at an elevation with respect to the sides and said roller having its elevated end flared from a point opposite the outwardly rounded ends of the sides.

5. A rerailing frog comprising a base having upstanding flanges adjacent to the

outer edges thereof and comprising two sections, having an interengaging tongue and groove, the base, from one end thereof, having its upper face channeled longitudinally and the sides of the base being inclined from the last mentioned end to a point adjacent the second end thereof, the elevated end of the sides being straight and said sides at the upper portion thereof having an outwardly extending head which extends beyond the elevated end of the sides proper, a toe including a body member having a tongue received in the groove of the base and having an upstanding web whose outer face is grooved longitudinally, means securing the body to the sides of the channel

member for associating both of these members, a toe member having a body portion received between the outwardly rounded ends of the sides and bolted thereto, said 20 toe and heel member being elevated above the heads of the sides, a roller having trunnions on the ends thereof journaled respectively in the toe and in the heel, said roller being flared outwardly at the elevated end 25 thereof, and a hook swivelly connected to the heel.

In testimony whereof we affix our signatures.

KIRK S. HOOKS.
